Oscar Johnson

Attorney

UNITED STATES PATENT OFFICE

OSCAR JOHNSON, OF GLENDALE, CALIFORNIA

GRIPPING DEVICE

Application filed July 21, 1928. Serial No. 294,405.

My invention relates to a device for gripping articles, and particularly articles of a soft, pliable or limp nature such as textile fabrics, and it has more especial reference to 5 a device by which articles of wear and particularly limb or finger encasing apparel or portions thereof, as socks, hosiery, sleeves and the like, or in fact any textile casing or envelope, may be turned inside out.

10 The objects of the invention are to provide a simple and inexpensive means by which articles of wear and use may be reversed, whether wet or dry; and to provide a device of this character that is easily manipulated, light and will not injure the articles gripped thereby.

15 A preferred form of the invention is illustrated in the accompanying drawing, forming a part of this specification, and therein 20 Fig. 1 is an elevational view of a device embodying my invention.

Fig. 2 is an enlarged sectional plan view, the section occurring on line 2—2 Fig. 1.

25 Fig. 3 is a perspective view showing the device inserted in a garment.

Fig. 4 is a perspective view showing the device as actually used in the reversal of a garment, and

30 Fig. 5 is an enlarged detail of a modified part of the device.

Like numerals of reference in the drawing denote like parts. The invention consists of a frame of desirable length, having at one end a handle and provided with means operable by the thumb or other member with respect to the opposite end thereof for gripping an article. In the particular and chosen form illustrated in the drawing, the invention is shown as comprising a frame 1, 35 preferably of narrow width and of a length desirable for the particular uses thereof. To one end of the frame 1 is secured or provided a handle 2, and the opposite end thereof is provided or formed with a guide 3, through 40 which is extended for relative movement a rod 4, having at one end thereof a knob, hook or enlargement 5 of a size relatively greater than the guide 3. The other end of said rod 4 is provided with a thumb or finger engaging member 6, that is disposed within con-

venient reach of the thumb or finger of the hand which grips or holds the handle 2, and by which the rod 4 is arranged to be operated relatively to the guide in the frame 1 and the knob, hook or enlargement 5 thereof is 55 caused to be moved with respect to the end of the frame when gripping or releasing an article, as explained later.

In the instance of the embodiment of the invention, as shown, and for purposes of light construction and economical manufacture, the frame 1 consists of a single piece of suitably rigid wire bent intermediate its length to form or provide an eye, which constitutes the guide 3 heretofore mentioned. The wire is then bent upon itself at each side of the eye 3 and at substantially right angles thereto to form substantially parallel spaced frame portions 1' and 1'', each of which, near the end opposite the loop end is formed with an off-set, as shown at 7 and 7', and the extreme ends of which are securely contained in the handle 2. Through the loop or guide 3 is extended for operation the rod 4, the end of which is provided with the knob, hook, or other enlargement 5. The other end of the rod 4, which is disposed centrally between the parallel spaced frame portions 1' and 1'', is provided with a thumb or finger engaging member 6 which in the specific form shown, 70 comprises a loop, which encircles and is slidably associated with the narrowed frame portions 8 and 8' between the handle 2 and the offsets 7 and 7', which latter serve to limit the forward movement of the loop 4' and 75 consequently of the rod 4.

In practice, the handle 2 being grasped by the hand of the user, as illustrated in Figs. 3 and 4, the frame 1 of the device is inserted inside a garment or other article that it is 80 desired to reverse. The loop or member 6, which is within convenient reach of the thumb or other member of the hand holding the device, is then operated toward the offsets 7 and 7' causing thereby the knob, hook or enlargement 5 on the end of the rod 4, to be moved away from the eye or guide 3 in the end of the frame 1, as shown in Figs. 1 and 3. With the other hand, the user then 85 presses or draws the material of the garment 90

against the projected rod 4 between the end of the frame 1 and the knob 5 of the rod 4. Thereupon the loop 6 is retracted causing the material of the garment to be gripped by the head or knob 5 on the rod. By then withdrawing the frame with the material at one end of the garment gripped thereby, while the other end of the garment is held by the other hand, as shown in Fig. 4, a reversal or turning inside-out of the garment is effected, be the garment dry or wet.

I have shown the device as especially adaptable to the reversal of textile articles, but mean no limitation thereby of the uses to which the invention may be put, it being also readily usable for gripping articles that may be immersed in hot or cold water.

In Fig. 5 I have illustrated a modified form of guide that may be employed, particularly where the device needs to be of considerably heavier material. In this case, I provide a metal head 9 that is preferably hollow, and provided with sockets 10 and 10', into which the respective ends of the frame portions 1' and 1" are rigidly fitted. The upper end of the head 9 is provided with an opening 11, serving as a guide for the rod 4.

What I claim, is:

1. A device for reversing garments comprising a wire frame having a handle at one end and a guide at the opposite end and formed near the handle end with an offset, a rod extended through said guide and provided with a knob at one end, and a loop for slidably connecting the other end to said frame, said loop arranged for engagement by the thumb or other member to operate said rod and cause movement of the knob thereof relative to the end of said frame to grip or release a garment, said offset on said frame serving to limit the movement of said rod in one direction.

2. In a device for reversing garments, a wire frame having a pair of outwardly bowed members, at one end provided with a guide opening and at the other end provided with a handle, a rod extending through said guide opening and between said members and provided at one end with a knob arranged for co-operation with said guide opening to grip or release an article, and the other end of said rod bent around said frame members to connect said rod slidably with said members and arranged for engagement by the thumb or other member to operate said rod.

3. In a device for reversing garments, a wire frame comprising a pair of outwardly bowed members formed at one end with a guide opening and with offsets near the opposite end, a handle on the ends of said members, a rod between said members and provided at one end with a knob arranged for co-operation with said guide opening in gripping or releasing an article, said rod

provided with a loop encircling said frame members between the handle and the offsets thereof for slidably associating said rod with said frame, said loop arranged for engagement by the thumb or other member to operate same.

In testimony whereof I have set my hand.

OSCAR JOHNSON.
